UNITED STATES PATENT OFFICE

SOPHIA SOLOMON, OF BROOKLYN, NEW YORK, ASSIGNOR TO JOSEPH BERLINGER COMPANY, OF NEW YORK, N. Y., A CORPORATION OF NEW YORK

DESIGN FOR A TEXTILE FABRIC

Application filed December 27, 1932. Serial No. 46,619. Term of patent 3½ years.

To all whom it may concern:

Be it known that I, SOPHIA SOLOMON, a citizen of the United States, residing at the borough of Brooklyn, in the county of Kings and State of New York, have invented a new, original, and ornamental Design for a Textile Fabric, of which the following is a specification, reference being had to the accompanying drawing, forming part thereof.

The figure is a plan view of a textile fabric showing one-fourth of my new design intended to be used for a square scarf. The other 3 corners bearing the same design are arranged in proper relation to the detailed illustration to complete the pattern.

I claim:

The ornamental design for a textile fabric, substantially as shown and described.

SOPHIA SOLOMON.
